UNITED STATES PATENT OFFICE.

HARRY B. SYNAR, OF POUGHKEEPSIE, NEW YORK.

SASH OPENER AND FASTENER.

No. 808,586.

Specification of Letters Patent.

Patented Dec. 26, 1905.

Application filed January 4, 1905. Serial No. 239,629.

To all whom it may concern:

Be it known that I, HARRY B. SYNAR, a citizen of the United States, residing at Poughkeepsie, in the county of Dutchess and State of New York, have invented new and useful

Improvements in Sash Openers and Fasteners, of which the following is a specification.

This invention relates to combined locking and elevating devices for window-sashes, the object of the invention being to provide simple, reliable, and efficient means for raising the sash without any exertion on the part of the operator beyond releasing the sash-locking means and to provide coacting locking means whereby the sash may be held in any desired position.

Another object is to provide spring-motor mechanism for raising the sash which will be automatically wound or set by the downward movement of the sash and which will permit of the usual counterbalancing-weights being dispensed with.

With these and other objects in view the invention consists of the features of construction, combination, and arrangement of parts hereinafter fully described and claimed, reference being had to the accompanying drawings, in which—

Figure 1 is a vertical transverse section showing a sash and sash-frame equipped with the invention. Fig. 2 is a similar view, on an enlarged scale, through one of the spring-motors and associated rack-bar on the sash. Fig. 3 is a vertical section showing one of the motors in end elevation and also showing the associated locking mechanism. Fig. 4 is a fragmentary face view of the rack-plate, and Fig. 5 is a detail section on the line 5 of Fig. 1.

Before proceeding with a more detailed description it may be stated that in the form of my invention herein shown I employ means for locking the sash in closed position, and in connection with said sash I also employ suitable means by which on release or disengagement of the sash the same is operated to be elevated without exertion upon the part of the operator.

While my improvements are capable of use in connection with the ordinary window-sashes of houses and similar structures, they are especially adapted for car-windows, all as will be hereinafter more fully described.

Reference being had to the accompanying drawings by the designating characters marked thereon, 1 represents the frame of an ordinary car or similar window having the

hollow jambs or side pieces 2 and a sill or base piece 3 against which the lower sash closes, and 4 represents the lower sash, which is mounted to slide vertically in guides in the frame in the ordinary manner.

In accordance with my invention the frame 1 is extended below the sill 3 to form a base-compartment 5, and the side rails of the sash 4 are provided with downwardly-extending bars or legs 6, which when the sash 4 is closed extend down into the said compartment 5, as shown in Fig. 1. The inner faces of the bars 6 travel in contact with antifriction-rollers 7, carried by metallic plates 8, 70 suitably secured to the frame 1 within the compartment 5, these plates being arranged to have a slight yielding or spring movement to adapt said rollers to accommodate themselves to variations in the bars and sash due to climatic conditions. The rollers guide the bars in a determined path, and thus adapt the sash to freely move in the frame 1. The resilient plates 8 consist of comparatively thin long and narrow strips secured at their 80 ends in the window-frame in any preferred manner, but which may be, as shown, fitted in recesses formed in the sill 3 and bottom of the base-compartment 5, which construction will permit the plates to have the necessary 85 resiliency. Each strip carries a pair of bearing-rollers 7, arranged, respectively, near the upper and lower ends thereof. In order that the strips may fit close to the bars 6, they are preferably provided with slots 7^a to partially 90 receive the rollers 7, which latter are journaled in bearing-lugs 7^b, projecting from the outer faces of said strips on opposite sides of the slots.

To the outer side of each bar 6 is secured a 95 rack-bar or plate 9, having a series of teeth or recesses formed by equidistantly-arranged slots 10, as shown in Fig. 4. These rack-plates extend upwardly to a point above the sill-piece of the sash 4 and sill 3 of the frame 100 1 when the sash 4 is closed and are engaged by spur gear-wheels 11 of spring-motors arranged at the base of each side piece 2 of the frame 1. Each gear 11 comprises a series of teeth arranged upon a drum 12, having 105 closed end walls 13, pierced for the passage of a rod or shaft 14, on which the drum is mounted for rotation, the said end pieces of the drum being provided with sleeves 14', which project laterally therefrom and bear 110 at their outer ends against frame-plates 15, which are connected and held properly

spaced by tie-rods or bolts 16. The rod or shaft 14 is fixed at its ends in said plates 15, and arranged within the drum or casing 12 is a coiled spring 17, one end of which is made 5 fast to the intermediate portion of said shaft, as shown at 18 in Fig. 2, while the other end thereof is connected to the outer wall or periphery of the casing, as shown at 19. This spring is adapted to be wound up by the 10 retrograde rotation of the drum through the action of the rack 9 on the teeth of the gear when the sash 4 is lowered. When the motor is thus set or wound up and the sash 4 is released, the reaction of the spring in unwinding will rotate the gear to raise the sash without exertion on the part of the operator. By the use of two motor devices and gears of the construction described at opposite sides of the frame 1 the sash 4 will be evenly raised 15 and prevented from binding against its guides in the casing. When the sash is lowered, the bars 6, carrying the rack-plates 9, pass downward into the base chamber or compartment 5 and are thus concealed from 20 view. These bars are of such length as to permit the rack-plates to be formed with the required number of teeth to permit the gears to elevate the sash to its fullest extent.

The construction herein shown discloses 30 the application of the invention for the purpose of raising the lower sash of a window; but it will of course be understood that the operating parts may be duplicated at the top of the frame to enable the upper sash to be lowered or raised as desired without exertion on the part of the operator and locked in adjusted position by the locking mechanism, which I will now proceed to describe.

A latch, bolt, or dog 20 is provided to engage lugs 20' on the side of one of the gears 11 and is mounted to slide in a casing 21, set into the front face of one of the sides 2 of the window-frame, the said casing being closed at its inner or front side by a suitable cover-plate 22. The latch or dog 20 is provided with a reduced stem 23, which fits and slides in an opening in the plate 22 and is surrounded by a coiled spring 24, which normally serves to project the latch 20. In one of the 45 edges of the latch 20 is formed a recess 25, which is engaged by the free end of one of the arms of a lever 26, fulcrumed in the casing on a pin 27, the opposite arm of said lever having a slot receiving a pin 28 on the shank 50 of an actuating push-button 29. The shank of the push-button slides in an opening in the casing-cover 22, and the button itself is arranged to work within a socket 30 in the front or inner side of the window-casing, so 55 that by pushing the button inward with the thumb or finger the latch or dog 20 will be retracted and allow the gear-wheel to be rotated by its actuating-spring, thus raising the sash 4. The sash may be locked at any 60 elevation by releasing the button 29, where-

upon the spring 24 will project the latch into engagement with one of the lugs of the gear-wheel and hold the same from further rotation.

From the foregoing description, taken in 70 connection with the accompanying drawings, the construction and mode of operation of the invention will be understood without a further extended description.

Changes in the form, proportions, and minor details of construction may be made within the scope of the invention without departing from the spirit or sacrificing any of the advantages thereof.

Having thus described the invention, what 80 is claimed as new is—

1. In a sash elevating and locking means, the combination of a window-frame, a sash provided upon its side bars with rack-teeth, motor-gears arranged at the opposite sides 85 of the window-frame and engaging said rack-teeth, means for locking the motor-gears against rotation, yielding pressure-bars mounted on the frame and coextensive in length with the range of travel of the sash, 90 and friction-rollers arranged in spaced relation upon said bars and held with yielding pressure thereby against the side bars of the sash to guide the same in its movements.

2. In a sash elevating and locking device, 95 the combination of a window-frame, a sash provided upon its side bars with rack-teeth, motor-gears arranged at opposite sides of the window-frame and engaging the rack-teeth, means for holding the sash against movement, spring pressure-plates arranged in the frame and coextensive in length with the range of travel of the sash, and a pair of rollers mounted upon each pressure-plate adjacent the ends thereof and adapted to bear 100 with yielding pressure against the side bars 105 of the sash to guide the latter in its movements.

3. In a sash elevating and locking device, 110 the combination of a sash provided with rack-teeth, a spring-actuated motor-gear mounted on the frame and engaging said rack-teeth, and locking mechanism for holding the gear against rotation, said locking mechanism comprising a sliding spring-actuated 115 bolt adapted to engage the gear, an intermediate-pivoted lever connected at one end with the bolt and a sliding finger-piece pivotally connected with the opposite end of the lever, the window-frame being provided with 120 a socket for the reception and free movement of said finger-piece, substantially as described.

4. In a sash elevating and locking device, 125 the combination of a window-frame, a sash provided with rack-teeth, a spring-actuated motor-gear engaging said teeth, a casing mounted upon the window-frame, a sliding locking-bolt movable in an opening in said casing and adapted to engage the gear, said 130

bolt having a stem guided by the casing, a spring surrounding said stem between the casing and bolt and serving to normally project the bolt, a lever intermediately pivoted in said casing and connected at one end with the bolt, and a sliding finger-piece movable in an opening in the casing and pivoted to the other end of the lever, whereby the latter may be actuated to retract the bolt against the pressure of its spring, the sash-frame be-

ing provided in its inner face with a receiving socket or recess, and a button or head upon the finger-piece movable into said socket or recess.

In testimony whereof I affix my signature 15 in presence of two witnesses.

HARRY B. SYNAR.
